UNITED STATES PATENT OFFICE

ANTON FRANK BROTH, OF KOHLER, WISCONSIN, ASSIGNOR TO KOHLER COMPANY, OF KOHLER, WISCONSIN, A CORPORATION OF WISCONSIN

THERMOSTATIC SWITCH

Original application filed October 5, 1925, Serial No. 60,702. Divided and this application filed March 31, 1927. Serial No. 179,934.

This invention relates to thermostatic switches for effecting the opening or closing of an electrical circuit with a snap action.

An object of the invention is to provide a switch member responsive to slow action of a thermostatic or heat element and which, when moved thereby to a certain point, will be automatically carried beyond that point with a quick action effecting a speedy operation of the switch.

Another object of the invention is to provide a thermostatic switch of this character required to be reset by hand for compelling attention to the condition responsible for the temperature change causing the operation.

A further object is to utilize a bow spring for holding the switch member with spring pressure in either its open or closed position.

Another object of the invention is to provide such a thermostatic switch particularly designed for disconnecting the cranking circuit of a gas-engine-operated generating unit of the demand starter type when cranking is ineffective.

This case constitutes a division of my application for Automatic generating plants, Serial No. 60,702, filed October 5, 1925.

With the above and other objects in view the invention consists in the thermostatic switch as herein claimed and all equivalents.

Referring to the accompanying drawings in which like characters of reference indicate the same parts in different views,

Fig. 1 is a front view of a thermostatic switch constructed in accordance with this invention, the casing in which it is contained being sectioned longitudinally;

Fig. 2 is a side view thereof, the casing being sectioned transversely and the switch being in its closed position;

Fig. 3 is a similar view with the switch in its open position;

Fig. 4 is a detail view showing the guide member for the resetting rod, and

Fig. 5 is a detail view of the spring.

In these drawings, 11 indicates one of a pair of end castings connected by a bottom member 12 and supporting between them a panel 13 of slate or other suitable insulating material. The switch-box thus formed is

closed by a bent-over cover plate 14, which is pivotally mounted at the rear of the switch-box to the end castings 11 so as to be capable of swinging open to expose the switches contained therein, only one of which is here shown, being the thermostatic switch of this invention.

The various switches contained in the switch-box in the mechanism as designed are those necessary for the automatic operation and control of a gas-engine-operated generating unit of the demand starter type and the thermostatic switch here shown is provided for automatically opening the cranking circuit after a period sufficient for cranking so as to prevent depletion of the battery when for any reason the engine cannot be cranked, as upon the absence of fuel, and this consists of a heating coil 30 secured to a strip of bi-metallic thermostat metal 31 which is mounted at one end on the insulating panel 13 and at the other end carries a contact 32 to engage a contact 32 carried by a lever 33 mounted on a pivot-block 34 and held in either its closed or its open position by an arched spring 35 engaging said pivot-block and a projection of the lever. This spring serves to hold the lever in either of its positions by having its outer end carried from one side to the other of the line connecting its inner end and the pivotal axis of the lever. A resetting rod 36, serving as an indicator to show by its projection through an opening in the switch cover 14 that the thermostat switch is open, is pivotally mounted on the lever 33 and is guided by passing through an opening in a guide member 37 mounted on the upwardly extending front flange 38 of the bottom member 12.

Without entering into the details of circuit connections which are not essential to an understanding of the present invention, it is sufficient to note that the contacts 32 are included directly or indirectly in the cranking circuit which it is desired to interrupt upon a failure of cranking, and the heating coil 30 of the thermostatic switch for disconnecting said contacts when the engine fails to crank within a reasonable time is in a circuit controlled by the means

which controls the cranking circuit so that the heating influence thereof is concurrent with the cranking effort and is ineffective for moving the thermostat element a sufficient degree to disturb the circuit connections during the normal periods of cranking. However, a failure of the engine to crank for any reason, as in the absence of fuel, does not deplete the battery by a continuous operation of the generator as a motor, but after a reasonable predetermined time the heating effect of the heat coil 30 causes the thermostat strip 31 to bend and gradually force the lever 33 outwardly against the action of spring 35, meanwhile rubbing the contacts together until the spring passes over the dead center and throws the lever to its outermost position, opening the contacts 32 with a snap action and consequently interrupting the cranking circuit. In this position the lever 33 is held by the spring 35 with the rod 36 projecting from the cover of the switch-box to indicate that the thermostatic switch is open. When the defect has been remedied, as by providing a supply of fuel if that was the cause of the failure to crank, the thermostatic switch has to be reset by hand by pressing the rod 36 inwardly to close the contacts 32.

30 What I claim as new and desire to secure by Letters Patent is:

1. A thermal switch comprising a base, a lever pivotally mounted thereon, spring seats formed on the lever and the base, the line 35 joining which passes through the pivotal axis of the lever in an intermediate position of the lever, a spring with its ends fitting in said spring seats, a contact carried by the lever, a suitably mounted strip of thermostat metal, and a contact carried thereby engaging the 40 contact of the lever.

2. A thermal switch comprising an insulating panel, a cover therefor, a base mounted on the panel, a lever pivotally mounted 45 on the base, a bowed spring confined between the base and the lever, the line connecting the ends thereof passing through the pivotal connection of the lever in an intermediate position of the lever, a contact carried by 50 the lever, a strip of thermostat metal mounted on the panel, a contact carried thereby for engaging the other contact, a heating coil 55 carried by the thermostat metal, and an indicator and resetting rod carried by the lever and projecting through an opening in the cover.

3. A thermal switch comprising an insulating panel, a bottom member secured thereto, a removable cover forming an enclosure 60 with the panel and bottom member, a base secured to the panel, a lever fulcrumed on the base, a spring between the base and the lever, the line connecting the ends thereof passing through the fulcrum point of the 65 lever in an intermediate position of the lever,

a contact carried by the lever, a strip of thermostat metal secured to the panel, a heating coil carried thereby, a contact on the thermostat metal engaging the other contact, a guide on the bottom member, and an indicating and resetting rod carried by the lever and passing through the guide and through an opening in the cover.

4. A thermal switch comprising a suitably mounted strip of thermostatic metal, an electrical contact carried thereby, a pivotally mounted switch member having dead center spring action for urging it to either of two positions, and an electrical contact on said switch member for engaging the electrical contact of the strip of thermostat metal, said switch member being responsive to slow action of the strip of thermostat metal and when moved thereby to a certain point being automatically carried beyond that point with a quick action effecting a speedy opening of the electrical contacts.

In testimony whereof, I affix my signature.

ANTON FRANK BROTZ.
